UNITED STATES PATENT OFFICE.

ALFRED JOHN DUNN, OF BIRMINGHAM, ENGLAND.

CONCRETE AND LIKE STRUCTURE.

1,375,903.

Specification of Letters Patent. Patented Apr. 26, 1921.

Application filed December 23, 1918. Serial No. 267,974.

To all whom it may concern:

Be it known that I, ALFRED JOHN DUNN, F. R. I. B. A., subject of the King of Great Britain, residing at Clarendon Chambers, 5 Waterloo street, Birmingham, England, have invented certain new and useful Improvements in and Relating to Concrete and like Structures, of which the following is a specification.

10 This invention comprises improvements in and relating to concrete and like structures and has for its object to improve the construction and facilitate the erection of concrete and like buildings or structures.

15 While the more usual method of reinforced concrete construction at present in use consists of casting the main members, such as pillars, piers, etc., *in situ*, between what are termed shuttering boards, which 20 are temporarily erected to form the molds for such cast members, it is known to form the piers and like members separately as completely formed units and to place them in position and cast the walling, or build it 25 up of concrete slabs previously made, between such main members; the walling or slabs in some cases entering dovetail or other recesses in the main members.

The object of my invention is to improve 30 the construction of concrete pillars, corner pieces, piers, intermediate standards or like vertical members, to secure more effective keying of cast concrete or cement walls and the like thereto to enable the walling to be finished flush with the members when desired 35 avoiding unsightly projections of the members, and to facilitate fixing in position the door and window frames.

The pillars, corner pieces, standards, and 40 the like are formed with a central body portion, which may be solid and reinforced in any suitable manner, if desired, of substantial cross section, from which keying nibs or fillets project. The projecting keying nibs 45 or fillets are formed with angular terminal edges, each edge being preferably in the central vertical plane of the projection, and the preferred inclination for the sides of the angular edge is such that the angle between them is a right angle. It is preferred 50 that the oppositely inclined edges of the angular edge directly meet the respective plane sides of the body of the standard pillar or the like so that no intermediate shoulder is formed between the plane sides of 55 the member and the inclined sides of the

keying edge, so that flush finishing of the walls and members may be effected. It will be understood that the relative inclination of the sides of the angular edge may vary 60 from the right angle above specified, but that is believed to be the most effective compromise between the better keying effect of a more pronounced angular projection with the cast concrete and the lateral strength of 65 the projection and its liability to fracture from shock or otherwise.

It will be understood that one, two, or more of these keying nibs or fillets will be formed on each face of a member to which 70 a wall, partition or the like is to be formed by casting operation or by slab work erection in the known manner. Where two projections from the face of a member occur it is preferred to have the intervening space 75 equal to the width of the base of the angular fillet or nib, but this is not essential and the space may be larger or less as desired.

In conjunction with such filleted members the sole members or beams or brestsummers 80 may have a central projecting cog or rib on one or more faces which cog or rib in width corresponds with the intervening space between the projecting keying fillets from the pillars, standards, or the like. 85 The pillars, standards, or the like at their upper and lower ends have projections leaving an intervening space and thus the pillars, etc., may be interlocked on a cogged sole or sill at the base and may have a 90 cogged or ribbed beam, brestsummer or the like similarly interlocked with their upper ends, on to which beam or the like further standards may be locked, and so on, which greatly facilitates the erection of a prepared 95 concrete or like skeleton to receive the concrete walls and the like, which are cast *in situ* onto the keying nibs or fillets of the main members.

Similarly window or door jambs, whether 100 of wood or of concrete, may have projections to enter the intervening spaces, between the projecting fillets, of pillars, standards, and the like, and flared away sides to seat against the angular faces of 105 the said keying fillets or nibs to facilitate their fixing. Similarly the window or door heads or lintels and sills may be cogged or grooved and locked in position whether on the top or the underside, according to the 110 class and position of the member.

The central cogging or ribbing of beams,

breastsummers and the like in addition to permitting joggle jointing of the same with the pillars, standards, and the like, forms supporting ledges or abutments for receiving the cast concrete or slab work walls, floors, or the like. I do not claim *per se* the idea of a keying projection and recess between piers and the like and sills, sole members or beams as this has been proposed before.

On the drawings: Figure 1 is an isometric view showing my improved construction of piers or like main members and beams, and shuttering for casting in the walling.

Fig. 2 is a vertical sectional view of a wall of a two story building.

Fig. 3 is a sectional plan showing various forms of vertical members in use, and shuttering for the walls is shown in position.

Figs. 4, 5, 6, 7, and 8 are sectional views of vertical members for single wall construction.

Figs. 9, 10, 11, 12, and 13, are isometric views showing the connections of such members to sole plates and the connection of beams and the like to the members.

Figs. 14, 15, 16, 17, and 18, (Sheet 2) are sectional views of vertical members for double or cavity wall construction.

Figs. 19 to 23, show the construction of the bottoms and upper ends of the members shown at Figs. 14 to 18 for their connection to sole plates and for the connection of beams and the like to them.

Fig. 24 (Sheet 3) shows in horizontal section the mounting of a door on a single wall member.

Figs. 25 and 26 are similar views to Fig. 24 showing respectively an inside and an outside door mounted to members of double or cavity walls.

Figs. 27 and 28 (Sheet 4) are isometric views showing respectively a window head and sill mounted to double or cavity wall members.

Fig. 29 (Sheet 1) is a detail of a securing device for the supporting members of shuttering boards.

Fig. 30 is a detail of a special form of wall tie which supports internal shuttering boards.

Fig. 31 shows counter wedges for securing internal shuttering boards.

As shown in Figs. 1, 2, and 3, the main vertical members, stanchions, piers, or the like, are formed with a solid and suitably reinforced body *a* and one or more keying and locking fillets or nibs *b* projecting from the body. Each nib or fillet has an angular terminal edge, as set out above in the general statement of the invention and which is clearly shown at *b*. It will be understood that the cross section of the vertical members will depend on the particular purpose of use. At Fig. 1 the vertical piers shown

are for use with double or cavity walling and consequently from each face to which a wall adjoins, two angular edged fillets *b* project. Fig. 3 shows a typical main wall structure introducing a corner piece *c* between main walls of double or cavity form, a pier at *d* between two lengths of walling, a further pier at *e* to which a single thickness party wall is joined, and a smaller intermediate member in a main wall at *f*. From this typical example and the various cross sections of vertical members for use in single walls, shown at Figs. 4 to 8, and for cavity walls as shown at Figs. 14 to 18 the nature of the construction to be provided to meet ordinary cases will be clearly understood.

The cast concrete walling is keyed effectively to the piers or other vertical members by being cast upon the fillets *b*, and in a similar way slab work may be keyed to the vertical members if the end slabs are formed with recesses corresponding to the angular fillets *b*.

To lock the vertical members upon sole pieces or the like each vertical foot of the member is formed with a groove *g*, see Fig. 1, Figs. 9 to 13, and Figs. 19 to 23, which groove *g* sets over a cog *h* of the sole piece or like horizontal member.

Similarly the upper ends of the vertical members are provided with grooves *j* to receive cogs *k* formed upon the horizontal members, such as beams and the like which are supported on the vertical members. Figs. 9 to 13 and 19 to 23 show particular examples of the forms of the grooves *j* in the vertical members to suit various conditions of use as there illustrated.

By means of this jointing between the vertical members and the horizontals the erections of the main skeleton of a building is greatly facilitated as the individual members are much more readily retained in position while the casting in of the walling or the erection of slab walling takes place. Further the continuous cogs *k* upon the horizontal members form supporting edges between the vertical members to receive the cast or slab walling, and where double walling is used, insure the locking of the walls to the horizontal members as well as to the vertical members.

As shown at Fig. 24 a door frame *l* may be grooved for mounting upon the angular fillet *b* of a member *a*; the door is shown at *m* and architraves at *n*. At Fig. 25 an inside door is shown mounted to a double fillet member *a*. In that case a jamb lining *o* is provided at intervals with furring or distance blocks *p* shaped to fit the space between the fillets *b* and triangular wood or like fillets *q* are employed on the outer sides of the fillets *b* of the member *a*. For an outside door a stout door frame *r* fitting be-

tween the fillets *b* and shaped to seat against the angular faces of same is all that is required. The door head will in each case be notched or grooved in its ends to seat upon the fillets *b* of the member *a*.

Similarly with window frame mountings, an example of which is shown in Figs. 27 and 28, the jamb *s* is shaped to fit within and against the two fillets *b* and the ends of the head *t* Fig. 27 and sill *u* Fig. 28 are grooved or notched at the ends to seat on the angular fillets *b*. For cavity walling it is preferred to cog these parts with the continuous cogs *k* as with the other horizontal members before described. The figures show concrete cement or like frames but wood frames may be similarly arranged.

For the purpose of supporting shuttering boards to the main members for casting concrete, cement, or like walls or partitions thereto, I may provide angle irons as at *v* Figs. 1, 2, and 3 supported at the bottom by a clamping bolt *w*, passing through the sill or sole member from one side to the other. At the top the angles are supported by yoke pieces *x* and cross bolts *y* and by means of the construction of the yoke *x* shown at Figs. 1 and 29 which clamps over the beams or other horizontal members and has a series of holes *z* in the vertical limbs, vertical adjustment may be readily effected. Lateral adjustment may also be provided as shown at 1 Fig. 29 so that the vertical limbs may be spaced out from the angles by distance piece 2 slipped over the bolts *y* to accommodate moldings or the like formed on the horizontal members. At Figs. 1, 2, and 3, the shuttering boards are shown in place for the casting in of the double or cavity walls 3, the outer shuttering boards 4 being secured against the vertical members by the angles *v* and the inner boards 5 may be dropped into special wall ties 6 Fig. 30, which have central taper projections to insure correct placing of the boards and the superposed boards which are inserted, as the work proceeds may be secured by counter wedges or co-acting inclines as at 7 Fig. 31. One of the counter wedges is provided with 50 side flanges and with an overhanging anchoring flange 8 to maintain its position.

Instead of the square cogs *k* upon the horizontal members I may employ angular projections similar to the fillets *b* of the vertical members, or projections with plane end surfaces and taper sides, the grooves of the heads and feet of the uprights being correspondingly shaped to receive the projections.

The vertical members instead of being formed as complete units may be comprised of a number of cast blocks suitably connected together but provided with the angular fillets so as to conform to the unitary

structures illustrated. The tops and bottoms of these blocks will be grooved and cogged 65 similar to the top of the vertical members and under sides of the beams already described. If lateral keying means be desired keys can be inserted in lateral slots cut in the members.

I claim:—

1. In a structure of the class described, a vertical member having a vertical fillet or fillets on one side, each fillet being provided with oppositely beveled faces which 70 converge to form an edge, said faces being at right angles to each other, and a molded wall member one end of which is joined to said vertical member and keyed by said fillet.

2. In a structure of the class described, a vertical member having a vertical fillet or fillets on one side, each fillet having oppositely beveled faces which converge to form an edge, said faces being at right 85 angles to each other, the fillets terminating flush with the plane surfaces of the member to enable the walling to be finished flush with the member, and a molded wall member one end of which is joined to said vertical member and keyed by said fillet.

3. In a structure of the class described, a vertical member having a vertical fillet on one side provided with oppositely beveled faces which converge to form an edge, 95 said faces being at right angles to each other, said member also having a recess in one end extending thereacross; a horizontal member extending across said end of said vertical member and having a projection 100 engaged in said recess, and a molded wall member in the angle between said vertical and horizontal members and keyed at one end by the said fillet.

4. In a structure of the class described, 105 a vertical member having spaced vertical fillets on one side each of which is provided with oppositely beveled faces which converge to form an edge, said faces being at right angles to each other, said member also 110 having recesses in the ends, extending thereacross and arranged between said fillets; upper and lower horizontal members extending across the ends of the vertical member and having longitudinal flange projections on their opposing sides, end portions of which are engaged in said recesses of the vertical member, and spaced and molded wall members between said vertical and horizontal members, spaced apart by the 120 intermediate portion of the flange projections of the horizontal members and having ends joined to said vertical member and keyed by the said fillets thereof.

In testimony whereof I affix my signature. 125
ALFRED JOHN DUNN,
